WHEEL SHROUD FASTENER

Arthur Claud-Mantle, Trumbull, Conn., assignor
to The Bassick Company, Bridgeport, Conn., a
corporation of Connecticut

Application June 20, 1941, Serial No. 398,943

9 Claims. (Cl. 292—214)

This invention relates to an improved fastener or catch for a shroud or panel associated with the fender of a motor car. The shroud is in the form of a plate received in an opening at the side of the fender, and when assembled with the fender the shroud provides a skirt portion concealing the wheel to a large extent.

When the wheel is to be removed it is necessary to remove the shroud, and it is manifestly desirable that the shroud fastener be easily, conveniently and quickly manipulable. It is also desirable that the shroud be capable of easy, convenient and quick reinsertion into its seat in or on the fender structure. It is also desirable that the fastener have an effective holding or latch action without looseness or play, and that the fastener device be easily accessible for manipulation. The fender and shroud structure should also be satisfactory from the standpoint of appearance.

One of the objects of my invention is to provide a wheel shroud fastener which meets the above mentioned conditions.

Another object is to furnish a simple, compact and effective fastener device for holding in place wheel shrouds and similar elements.

To these and other ends the invention consists in the novel features and combinations of parts to be hereinafter described and claimed.

In the accompanying drawings:

Fig. 1 is a side elevation of a rear fender having a wheel shroud held in place therein by a fastener embodying my invention;

Fig. 2 is a view on a larger scale, partly broken away, showing the shroud as viewed from the inner side;

Fig. 3 is a section on line 3—3 of Fig. 2 but with the broken portions somewhat differently shown;

Fig. 4 is a partial view, similar to Fig. 3, showing the rocking rod in the released position;

Fig. 5 is an enlarged section on line 5—5 of Fig. 2;

Fig. 6 shows parts at the lower right hand portion of Fig. 2 on a larger scale;

Fig. 7 is a section on line 7—7 of Fig. 6;

Fig. 8 is a view similar to Fig. 7, showing the rocking rod moved to an extent in the releasing direction;

Fig. 9 is a view similar to Fig. 8, showing the rocking rod moved as far as possible in the releasing direction;

Fig. 10 is a section on line 10—10 of Fig. 6;

Fig. 11 is a detail of the mounting plate carried by the shroud;

Fig. 12 is a detail of the rotary shaft or stud; and

Fig. 13 is a detail section of the head portion of the rocker shaft actuated by the stud.

5 In the drawings, I have shown at 20 a rear fender of a motor car, said fender being cut away at its lower portion as indicated at 21 to provide a wheel-access opening which under ordinary circumstances is closed by a shroud 22. This shroud 22 is in the form of a panel or plate set in the wheel-access opening from beneath and fastened in said opening by means of a fastener indicated generally at 23.

10 My invention is particularly concerned with 15 the nature, structure and arrangement of the fastener which, broadly considered, comprises a rocking rod for holding the shroud in position and a rotary manipulating member by means of which the rod is moved from holding position 20 to the releasing position, and vice versa.

15 In the drawings, the rocking rod is indicated 20 generally at 24 and the manipulator or rod-moving element at 25, and in this form the manipulator is located intermediate of the ends of the 25 rod and has a manipulating portion projecting downwardly from the lower edge of the shroud at a point between the ends of the shroud.

20 As will be seen from Fig. 3, the fender structure 20 is provided at the ends of the opening 21 with flange portions 26 forming shoulders, and as will be seen from Fig. 5, a similar flange portion 26' forming a shoulder, is provided at the upper part of the wheel-access opening. These shoulder portions in conjunction provide a 25 forwardly facing seat indicated at 27 (and preferably including a rubber seating member 28) in which the shroud plate is received, said shroud plate being provided at the upper part with an inturned flange 29 and along the ends with inturned flange portions 29'. In order to reinforce the shroud plate and aid in holding it firmly in place, said plate is provided at suitable points in its length with inner transverse strips 30 suitably fastened thereto as by welding, these 35 strips each being provided at the upper end with a hook-like portion 31 (Fig. 5) adapted to straddle the adjacent flange portion on the fender. The hook-like portions 31 at spaced points in the length of the shroud plate serve to prevent inward or outward displacement of the upper portion of the plate relatively to the plate seat.

40 The fastener device 23 previously mentioned is carried by the shroud plate adjacent the lower margin of the latter and is supported upon an 45 inturned lip or flange 32 with which the plate is 50 carried by the shroud;

55

provided at its lower boundary. The rocking rod 24 previously mentioned is mounted within the lip or flange 32. This rocking rod has a body portion 33 and a crank-like intermediate portion 34 through which it is actuated by the rotary device 25 in a manner hereinafter described. The rocking rod 24 is further provided with crank-like extremities 35 which are extended past the ends of the shroud plate and act to fasten said plate in position in the manner hereinafter described. At certain points along the lower boundary of the shroud plate the rocking rod is provided with suitable bearings on the plate and for this purpose bearings 36 bent up from sheet metal may be employed, said bearings being secured to the lip or flange 32 in a suitable manner as by spot welding. These bearings 36 are at the upper side of the lip or flange 32.

The rocking rod is also mounted on the shroud plate by means of an intermediate mounting plate 37, which mounting plate serves also as a mounting for the manipulator or rod moving element 25. This mounting plate 37 is generally of angular form, having a horizontal flange 38 located above and against the flange 32, and an upwardly extending flange 39 disposed flatwise against the upright part of the shroud plate. The plate 37 is secured to the shroud plate in any suitable manner, as by spot welding. The mounting plate 37 extends inwardly somewhat beyond the inner edge of the flange 32, and in a region adjacent the inner edge of the flange 32 is provided with bent-up portions 40 serving as bearings for the rocking rod, these bearings 40 being located adjacent the respective sides of the crank portion 34.

At a point substantially in line with the bearings 40 the mounting plate 37 is provided with an opening 41, this opening being provided with a down-turned rim 42, and this opening serves as a bearing for a rotary shaft or stud member 43 which is a part of the manipulator 25. The stud member 43 has a portion extending downwardly from the shroud plate and adapted to be turned in a suitable manner, as by a wrench, and a portion extending upwardly into the space within the shroud plate and adapted upon rotation to shift the crank portion 34 and thereby the rocking rod to the fastening or latching position or to the released position.

In the particular form shown the stud 43 is short but of relatively large diameter and immediately below the rim 42 is provided with an integral collar 44 of greater diameter than the rim 42. Beneath the collar 44 the stud is provided with a polygonal wrench-engaging portion 45.

At its upper part the stud 43 is provided with a diametrical bore 46 and rotatably mounted in this bore is the smooth intermediate portion 47 of a transverse rocker shaft 48. This rocker shaft 48 serves as a means for engaging and moving the crank portion 34 of the rocking rod, and for this purpose the rocker shaft is provided at one end with a crank-engaging head 49 having a notch 50 in which the crank portion 34 is received. At the opposite end of the rocker shaft there is provided a balancing member 51 operating in the manner hereinafter described. This member 51 may as shown comprise a disk-like member adapted to bear against a washer 51a surrounding the stud 43 and supported against the body of the mounting plate 37. Member 51 fits over a reduced portion 52 on the 75

rocker shaft and is held in place by riveting over the extremity of the rocker shaft, as indicated at 53.

The head 49 previously mentioned is of greater diameter than the body of the rocker shaft so as to provide a shoulder 54 bearing against one side of the stud member 43, whereas the member 51 provides a shoulder bearing against the member 43 at the opposite side of the latter. The head 49 and its connected body portion are free to turn in the stud member and the member 51 is free to turn independently of the rocker shaft so as to act as a roller support. The notch 50 is so shaped that upon rotation of the stud member the crank portion 34 will be engaged to turn the rocking rod on its axis for the purpose of shifting the latching extremities of the rocking rod. The head 49 is bevelled off at one side, as shown at 55, and the notch 50 provided in the head is of a depth approximating the length of the head, being somewhat cut back at the respective sides of the head, as indicated at 56 and 57 respectively. In Fig. 3 is shown the position of the head 49 when the shroud plate is fastened in place, and in Fig. 4 is shown the position of the head in this particular case when the head is moved as far as possible in the releasing direction. From these views it will be seen that in this particular instance the movement of the head 49 is through substantially 180°, but obviously variation may be made in this respect.

Referring to Figs. 3 and 4, counter-clockwise movement of stud 43 beyond the position shown in Fig. 3 is prevented by engagement of head 49 with a stop member 58 projecting upward from the mounting plate. Similarly rotation of the stud member in a clockwise direction beyond the position shown in Fig. 4 is prevented by engagement of head 49 with an inclined stop member 59 provided at the inner edge of the mounting plate.

The crank-like extremities 35 of the rocking rod cooperate with fixed parts on and within the fender structure 20 in fixing the shroud plate in position. In the particular case illustrated, the fixed parts referred to are constituted by lugs 60 carried by the part 20 in a concealed position adjacent the lower edge portions of the wheel-access opening 21. The lugs 60 may advantageously be of angular form having flanges 61 suitably fastened, as by spot welding, to flange portions 62 extending along the lower boundary of the fender body, the lugs 60 also being provided with upright parts 63 which are adapted to be engaged by the crank portions 35.

One of the lug portions 63 is shown in Fig. 5, and it will be observed that at its upper inner part it is bevelled off to provide an inclined edge portion 64 with which the end portion of the corresponding crank portion 35 is adapted to cooperate. The lug parts 63 with their inclined surfaces 64 provide abutments in the fender structure at opposite sides of the wheel-access opening on which the latching extremities of the rocking rod are adapted to ride for giving the shroud plate an upward thrust, and it will be noted that the rocking rod being relatively long and made of light stock is adapted to be placed under a torsion action as hereinafter described.

For assisting in the latching action as hereinafter described the rim portion 42 extending downward from the mounting plate is provided with diametrically located downward projections 65 which are adapted to be engaged by

recessed portions 66 provided in the upper surface of the collar 44.

In placing the wheel shroud in position in the fender, the fastener device is preliminarily in released position such as shown in Fig. 4. In such position the intermediate crank portion of the rocking rod is disposed toward the inner side of the mounting plate. Such a position is also shown in Fig. 9. Fig. 9 also shows the relation between the intermediate crank portion and the crank extremities, this being an offset relation. In this particular case the crank extremities are offset almost 45° from the intermediate crank portions so that when the intermediate crank portion has the position shown in Fig. 9, in which it extends inwardly and somewhat upwardly, the crank extremities have positions in which they extend inwardly and somewhat downwardly. The fastener being in such a position, the shroud plate is engaged with its seat in the fender in an obvious manner.

The stud 43 is then engaged by a suitable wrench and turned in a counter-clockwise direction with reference to Fig. 4. In the following operation the head 49 travels from the position of Fig. 4 to the position of Fig. 3, moving meanwhile over a restricted part of the crank portion 34, said restricted part being a gently curved portion lying almost wholly to one side of the crank center and being indicated in the drawings at 34a. As the stud 43 is turned in the direction above stated, the head 49 in being moved in an arc turns on its axis and, traveling over the part 34a in one direction, cams the crank 34 upwardly until it lies directly over the upper end of the stud 43. Then as rotation of the stud is continued the head 49 begins to move in the reverse direction over the part 34a and swings the crank portion 34 over to the position shown in Fig. 3, where further movement is arrested by the stop 58. In these movements the rocker shaft is well balanced and supported by the roller 51 bearing against the washer 51a. While these movements have been taking place the crank extremities 35 have been lifted from the position of Fig. 9 to the position of Fig. 5 where the crank extremities are fully engaged with the surfaces 64, with the rocking rod under a considerable degree of torsion. As the rocking rod is placed under torsion the crank extremities engage the fixed inclined surfaces in a resilient manner and, the rocking rod being bodily carried by the shroud plate, the latter is forced home upwardly into its seat in a very effective manner.

As the shroud plate reaches the fully seated position, where it is resiliently held under a strong upward thrust, the recessed portions or notches 66 of the stud member snap into engagement with the projections 65 carried by the plate structure, with the result that the shroud plate is very effectively retained in place and any inadvertent or accidental dislodgement or displacement thereof effectively prevented. When, however, it is desired to have access to the wheel, the shroud plate can be easily, conveniently and quickly removed from the fender by applying a wrench to the stud member from below and turning the stud member in the opposite direction to that above mentioned. By a reversal of the operations previously described the crank extremities are moved rearwardly away from their cooperating inclined surfaces, as shown by the dotted lines in Fig. 5, and as soon as the crank extremities are clear of the upper ends of the lugs 60 the shroud plate is free

to be pulled down and then moved forwardly in order to remove it from the fender structure.

The easy, convenient and quick removal and reinsertion of the shroud plate is an important advantage of my invention. The fastener device has a very effective holding or latch action without looseness or play which would cause noise. Furthermore the construction is simple, compact and strong. The number of parts is reduced to a minimum. As the stud member projects downwardly from the lower edge of the fender structure it is conveniently accessible and at the same time it is so small and unobtrusive that a fender structure of pleasing, attractive appearance can be provided.

While I have shown herein only one form which my invention may take it is to be understood that the invention can be embodied in many and various forms and that various changes and modifications in the organization of parts and in the details can be made without departure from the principles of the invention or the scope of the claims.

What I claim is:

1. In a fastener for releasably securing a shroud plate in the wheel-access opening of a fender, in which the fender carries at opposite sides of the wheel-access opening fixed latching parts and the shroud plate carries latching means cooperating with said parts, a longitudinally disposed rocking rod carried by the shroud plate at its inner side and having crank-like extremities cooperating with said latching parts and also having an intermediate crank-like operating portion, and a rotary actuating member for said rocking rod carried by the shroud plate and turning on an axis approximately parallel to the general plane of the plate and connected to said operating portion so that upon rotation of said rotary actuating member the rocking rod is turned on its axis for latching or releasing the shroud plate.

2. In a fastener mechanism for securing a plate in an opening, a longitudinally disposed rocking rod carried by the plate at the inner face of the latter and having crank-like latching extremities projecting beyond the plate, said rod having an intermediate crank-like operating portion, and a rotary actuating member turning on an axis substantially at right angles to said rod and approximately parallel to the general plane of the plate, carried by the plate and connected with said operating portion of the rod so as to turn the rod on its axis and thereby swing its crank-like extremities, said rotary actuating member extending to and beyond one of the lengthwise edges of the plate and provided with a projecting portion by means of which it can be manipulated.

3. In a latching mechanism for a panel in which a torsion rod is employed having an intermediate bent crank portion at the rear of the panel, actuating means for the rod comprising a stud member mounted behind the panel for rotation on an axis parallel to the general plane of the panel and operably connected to said crank portion, said stud member projecting beyond one edge of the panel so as to be accessible for manipulation.

4. In a latching mechanism for a panel in which a torsion rod is employed having an intermediate bent crank portion at the rear of the panel, actuating means for the rod comprising a stud member mounted behind the panel for rotation on an axis parallel to the general plane of the panel and operably connected to said crank portion, said stud member projecting beyond one edge of the panel so as to be accessible for manipulation, and

said stud member being mounted in and projecting through a flange formed on one edge of the panel.

5. In a latching mechanism for a panel member in which mechanism a torsion rod is employed having an intermediate bent crank portion at the rear of the panel and adjacent one edge of the panel, actuating means for the rod comprising a stud member operatively connected to said crank portion and mounted for rotation on an axis substantially parallel to the general plane of the panel, said stud member projecting beyond the adjacent edge of the panel and the projecting portion having wrench faces.

6. In a latching mechanism for a panel member in which mechanism a torsion rod is employed having an intermediate bent crank portion at the rear of the panel and adjacent one edge of the panel, actuating means for the rod comprising a stud member operatively connected to said crank portion and mounted for rotation on an axis substantially parallel to the general plane of the panel, said stud member projecting beyond the adjacent edge of the panel and the projecting portion having wrench faces, and means associated with the outer end portion of the stud member for preventing dislocation after the torsion rod has been moved to the latching position or the releasing position.

7. In a latching mechanism for a panel member adapted to be inserted into a notchlike opening and having an inwardly directed flange at that edge of the panel located at the outer side of the opening, a torsion rod disposed behind the body of the panel and extending longitudinally of the panel adjacent the flange at the inner side of the latter and having cranklike latching extremities, members on the flange serv-

ing as bearings for the rod, and rod turning means extending through the flange from the outside and connected to the rod intermediate of its ends.

5 8. In a latching mechanism for a panel member, a torsion rod mounted at the rear of the panel member and having cranklike latching extremities and a cranklike intermediate operating portion, a rotary shaftlike operating member for

10 the rod having its axis generally perpendicular to the rod, said shaftlike member having an operating end remote from the rod, and a rocker shaft journaled in the other end portion of said shaftlike member and adapted to turn therein on an axis substantially perpendicular to the axis of said shaftlike member and provided at one end and at one side of the shaftlike member with a fork operatively engaged with the cranklike operating portion of the torsion rod.

15 9. In a latching mechanism for a panel member, a torsion rod mounted at the rear of the panel member and having cranklike latching extremities and a cranklike intermediate operating portion, a rotary shaftlike operating member for

20 the rod having its axis generally perpendicular to the rod, said shaftlike member having an operating end remote from the rod, a rocker shaft journaled in the other end portion of said shaftlike member and adapted to turn therein on an axis substantially perpendicular to the axis of said shaftlike member and provided at one end and at one side of the shaftlike member with a fork operatively engaged with the cranklike operating portion of the torsion rod, and

25 means at that end of the rocker shaft which is opposite the fork for supporting the rocker shaft against lateral thrust.

ARTHUR CLAUD-MANTLE.
